UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,396,672.

Specification of Letters Patent.

Patented Nov. 8, 1921.

Application filed November 27, 1920. Serial No. 426,700.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby when the filling in the shuttle becomes substantially exhausted, a change in the loom operation is effected.

The feeler mechanism of the present invention is of the rotary type wherein, when a working supply of filling is present in the shuttle on a detecting beat, engagement of the feeler with the filling prevents rotative movement of the feeler about its longitudinal axis and when the filling is substantially exhausted on a detecting beat, the feeler is given its rotary movement to effect replenishment of filling. A rotary feeler of the general character indicated is shown and described in the patent to Thomas Ferguson, No. 1,225,120, dated May 8, 1917, and the present invention is a further development of that type of rotary feeler and embodies improvements thereon, as will more fully appear.

One of the objects of the present invention is to provide a feeler mechanism of the rotary type which will be simple in construction, and more sensitive to the presence of filling in the shuttle and its substantial exhaustion on a detecting beat.

In the drawings:

Figure 1 is a perspective view showing a preferred construction of rotary feeler and the relation of parts when filling is present in the shuttle on a detecting beat;

Fig. 2 is a view similar to Fig. 1, showing the relation of parts when the filling is substantially exhausted on a detecting beat;

Fig. 3 is a perspective view of a modified form of a rotary feeler and its associated parts;

Fig. 4 is a plan view showing the relation of the feeler and its associated parts when a working supply of filling is present in the shuttle on a detecting beat;

Fig. 5 is a view similar to that of Fig. 4,

showing the relation of parts when the filling is substantially exhausted on a detecting beat; and

Fig. 6 is a front edge view of the feeler showing its spiral character.

The feeler of the present invention is formed with a spiral portion or blade, the axis of the spiral of which extends longitudinally of the feeler, and means is provided to coöperate with the spiral portion or blade of the feeler tending to turn it on its longitudinal axis as the feeler is moved frontwardly on a detecting beat. When a working supply of filling is present in the shuttle, however, the engagement of the toothed end of the feeler with the filling prevents rotary movement of the feeler, but when the filling is substantially exhausted on a detecting beat, the filling is no longer sufficient to prevent rotary movement of the feeler, and filling replenishment is thereby effected.

Referring more particularly to Figs. 1 and 2 of the drawings: the feeler stand 1 is adjustably mounted upon the loom frame 2 by means of the bolts 3 and slot 4. The feeler stand 1 has a front and rear bearing portion for a feeler carrier. In the present instance the front and rear bearing portions for the feeler carrier are constituted by upwardly extending lugs or flanges 5 and 6, respectively. Mounted for reciprocating movement in the front and rear bearing portions 5 and 6 is the feeler carrier 7. There are two general forms of feeler carriers now recognized in the art, one of which is constructed as a lever pivotally mounted on the loom frame, and the other of which is a slide; and the present invention is shown as associated with the slide form of feeler. The feeler carrier 7 has a frontwardly extending stem portion 8 on which is mounted the spring 9, one end of which bears against the front bearing 5 and the other end of which bears against a shoulder 10 formed on the feeler, the construction being such that the spring 9 normally acts to hold the feeler in its rearward feeling position with permissive movement frontwardly. A stop 11, which may be conveniently formed as a pin, serves to limit the rearward movement of the feeler carrier.

The rearwardly extending portion of the feeler carrier 7 is formed as a spiral 12 pref-

erably constituted as a twisted blade. Associated with the spiral or twisted blade 12 of the feeler carrier is the feeler 13 which has a spiral or blade 14. The spirals or spiral blades 12 and 14 are maintained in co-operative relation by means of pins 15 which may be conveniently seated in the spiral blade 12 of the feeler carrier and extend through the slots 16 formed in the spiral blade of the feeler, the construction being such that relative movement of the feeler and feeler carrier causes the spiral blade 14 of the feeler to turn axially as it is moved frontwardly relative to the spiral blade 12 of the feeler carrier. The rear end portion 17 of the feeler is provided with teeth or a roughened surface adapted to engage the filling 18 or the bobbin or filling carrier 19, as the case may be.

20 The feeler carrier and feeler are normally held in initial position as indicated in Fig. 1 by a yielding means such, for instance, as the spring 20 which may be conveniently coiled about a stud or pin 21 on the feeler carrier and has an end portion 22 for engagement with the feeler, the construction being such that after the feeler and feeler carrier have been relatively moved by the frontward push against the feeler, the spring will normally return the feeler to its initial position relative to the feeler carrier.

When a working supply of filling is present in the shuttle on a detecting beat, the toothed end portion 17 of the feeler will sink into the filling and will prevent the feeler 13 from partaking of the rotary movement which tends to be imparted to it by the frontward pressure, and the feeler and feeler carrier will be moved frontwardly without disturbing their relative positions. When, however, the filling is substantially exhausted on a detecting beat, and is no longer sufficient to prevent the rotative movement of the feeler, the latter will be moved frontwardly and rotatively about the feeler carrier or blade 12; and advantage is taken of this relative movement of the feeler and feeler carrier to effect replenishment or filling.

In the present instance of the invention the rear end portions 6 of the feeler stand is provided with a transversely extending slot in which is slidably mounted the controller 23 having a slot 24 through which the feeler carrier 7 may freely pass. The slot 24 is elongated to permit the controller 23 to be moved transversely. The controller 23 is connected to a transmitter 25 which, by movement transversely by the controller 23, effects replenishment of filling through the usual train of mechanism well known in the art.

65 Mounted upon the feeler 13 is a controller actuator 26 which, in the present instance

of the invention, consists of an arm which may be secured to the spiral blade 14 of the feeler by means of a lug 27 and a set screw 28. The forwardly extending end portion of the controller actuator extends through a slot 29 of the actuator 23, the construction being such that when the feeler and feeler slide move frontwardly without relative movement on a detecting beat, the controller actuator 26 will slide frontwardly through 75 the opening or slot 29 of the controller without moving it laterally. When, however, the feeler is moved frontwardly and is turned upon its longitudinal axis owing to the depleted condition of the filling on a detecting beat, the controller actuator 26 will move the controller 23 laterally and effect replenishment of filling.

When the feeler 13 has been moved frontwardly relative to the feeler carrier, it will 85 be returned to its normal position as indicated in Fig. 1 by the spring 20.

In Figs. 3 to 6 inclusive, a modified form of the invention as indicated. In the modified form shown, the feeler stand 30 90 is provided with the flanges 31 and 32 through which extends the stem 33 of the feeler 34, and a spring 35 normally forces the feeler 34 into its rearward feeling position. A stop 36 limits the rearward movement of the feeler. Secured to the stem 33 and the feeler 34 is the spiral portion or spiral blade 37 and the rear end of the feeler is provided with teeth 38 for engagement with the filling or filling carrier on a de- 100 tecting beat.

The feeler stand 30 is adjustably secured to the loom frame 39 by a bolt 40 and slot 41 as indicated in Fig. 3.

Mounted at opposite sides of the spiral 105 blade portion of the feeler are the yielding bearing members 42, 43, which may be conveniently supported in the upstanding lugs 44 on the feeler stand. The yielding bearing members 42 and 43 are similarly formed 110 and comprise the flat plate portions 45 and laterally extending stems 46. A spring 47 on the stems 46 of each of the bearing members acts normally to cause the end portions 42, 43 of the yielding bearing members to bear upon 115 the opposite faces of the spiral portion or blade 37 of the feeler with permissive movement toward and from each other. One of the stems 46 of one of the yielding bearing members is connected to a transmitter 48 120 which, through a train of mechanism now well understood in the art, may effect replenishment of filling.

When a working supply of filling is present in the shuttle on a detecting beat, as indicated in Fig. 4, the toothed end portions 38 of the feeler 34 will engage and sink into the filling as indicated in Fig. 4, and prevent rotative movement of the feeler as it is moved frontwardly. As the feeler 34 is 130

5 moved frontwardly, Fig. 4, the spiral portion 37 of the feeler will cause a lateral movement of the yielding bearing members 42, 43, and owing to the connection with the transmitter 48, filling replenishment will be prevented. When, however, the filling is substantially exhausted on a detecting beat, as indicated in Fig. 5, the toothed end portion of the feeler 34 will 10 no longer be held from turning movement by the filling, and the feeler will be turned about its longitudinal axis owing to the pressure of the yielding bearing members upon the spiral or blade portion 37 as the feeler is moved frontwardly, the effect being that the yielding bearing members 42 and 43 will not be moved laterally or separated, and through the transmitter 48 and train of mechanism, filling replenishment will be effected.

15 In order to reduce, as far as possible, the frictional resistance to the feeler movement, the head portions of the yielding pressure members are preferably mounted for rotative movement as indicated in Fig. 4. Where the stem 33 is secured to the spiral blade 37, as by the pin 49, Fig. 3, the stem 33 is preferably made cylindrical so that it may turn with the feeler as the 20 latter moves frontwardly on a detecting beat when filling is substantially exhausted, as indicated in Fig. 5.

25 What is claimed is:—

30 1. In a feeler mechanism for looms, the combination of a feeler having a flattened spirally twisted blade and mounted for movement toward and from the front of the loom, and means acting upon the spiral blade as the feeler is moved frontwardly on a detecting beat tending to turn the feeler about its longitudinal axis and prevented from effecting such turning movement by engagement of the feeler with the filling on a detecting beat until substantial exhaustion 45 thereof.

35 2. In a feeler mechanism for looms, the combination of a feeler having a flattened spirally formed blade, means normally acting yieldingly to hold the feeler in rearward 40 feeling position with permissive frontward movement on a detecting beat, a feeler turner which acts upon the spiral blade as the feeler is moved frontwardly on a detecting beat and tends to turn the feeler but 45 which is prevented from effecting such turning movement by engagement of the feeler with the filling on a detecting beat until the filling is substantially exhausted.

50 3. In a feeler mechanism for looms, the combination of a feeler carrier, a feeler having a flattened spiral blade and mounted on the carrier for movement toward and from the front of the loom, means which acts yieldingly upon the spiral blade to turn the 55 feeler about its longitudinal axis when the

filling is substantially exhausted on a detecting beat, and means for effecting replenishment of filling when the feeler is turned about its longitudinal axis on a detecting beat.

70 4. In a feeler mechanism for looms, the combination of a feeler carrier mounted for movement toward and from the front of the loom, a feeler mounted on the feeler carrier and having a flattened spirally twisted blade, 75 and means acting upon the surface of the twisted blade tending to turn the feeler on a detecting beat and prevented from effecting such movement until the filling is substantially exhausted.

80 5. In a feeler mechanism for looms, the combination of a feeler carrier mounted for movement toward and from the front of the loom, a spirally twisted bladed feeler mounted on the feeler carrier and constructed and arranged to have a yielding turning force exerted upon it as it moves frontwardly, a transversely movable member adapted to be moved transversely by the turning movement of the feeler, and a transmitter connected to said member for effecting replenishment of filling when the twisted bladed feeler is turned about its longitudinal axis on a detecting beat.

85 6. In a feeler mechanism for looms, the combination of a feeler carrier having a spiral blade and mounted for movement toward and from the front of the loom, and a feeler mounted on the feeler carrier and having a spiral blade coöperating with the 90 spiral blade of the feeler carrier.

95 7. In a feeler mechanism for looms, the combination of a feeler carrier having a portion formed as a spiral, a feeler having a portion formed as a spiral, and means for 105 holding the spiral portions of the feeler carrier and feeler in coöperating relation with permissive relative movement.

100 8. In a feeler mechanism for looms, the combination of a feeler carrier having a portion formed as a spiral, a feeler having a portion formed as a spiral means for holding the spiral portions of the feeler carrier and feeler in coöperating relation with permissive relative movement, and means for 110 effecting replenishment of filling when the spiral portions are relatively moved on a detecting beat.

115 9. In a feeler mechanism for looms, the combination of a feeler carrier having a portion formed as a spiral, a feeler having a portion formed as a spiral, means for holding the spiral portions of the feeler carrier and feeler in coöperating relation with permissive relative movement, and means for 120 restoring the spiral portions of the feeler and feeler carrier to initial relative positions when such relative position has been disturbed.

125 10. A feeler mechanism for looms com- 130

prising, in combination, a feeler carrier having a rearwardly extending spiral portion, a feeler having a spiral portion held in cooperative relation with the spiral portion 5 of the feeler carrier, and yielding means which permits relative movement of the spiral portions of the feeler and feeler carrier.

11. A feeler mechanism for looms, comprising, in combination, a feeler carrier mounted for movement toward and from the front of the loom and having a spiral portion, a feeler having a spiral portion, means for holding the spiral portions in cooperative relation with permissive relative movement, and means for effecting replenishment of filling when the spiral portions

of the feeler and feeler carrier are relatively moved on a detecting beat.

12. In a feeler mechanism for looms, the 20 combination of a feeler carrier mounted for movement toward and from the front of the loom, a feeler having a spirally twisted portion adapted to impart a yielding rotating force to the feeler as it moves front- 25 wardly, a slide adjacent the feeler adapted to be moved transversely by the turning movement of the feeler, and means operated by said slide to effect replenishment of filling when the feeler is rotated as it is moved 30 frontwardly.

In testimony whereof, I have signed my name to this specification.

ISAAC SNOW.
